UNITED STATES PATENT OFFICE.

JOSEPH J. SMITH, OF CAMBRIDGE, MASSACHUSETTS.

DEVICE FOR OPERATING UPON THE CARDS OF CARDING ENGINES.

Application filed May 6, 1919. Serial No. 295,185.

To all whom it may concern:

Be it known that I, JOSEPH J. SMITH, a citizen of the United States, residing at Cambridge, in the county of Middlesex and State of Massachusetts, have invented certain new and useful Improvements in Devices for Operating upon the Cards of Carding Engines; and I do hereby declare the following to be a full, clear, and exact description of the invention, such as will enable others skilled in the art to which it appertains to make and use the same.

The present invention relates to devices for operating upon a card of a carding engine and more particularly to means for supporting the stripping roll of a card stripping device in operative position.

In prior commercial card stripping devices, the stripping roll is supported in operative position by means of brackets that project from the frame of the carding engine which are provided with sockets in which the ends of the shaft that carries the stripping roll are seated. The stripping roll in such devices is driven from the carding engine through a belt which passes over a pulley secured on one end of the shaft of the roll so that there is considerable tendency for the roll to be laterally displaced out of proper operative position relatively to the card cylinder. Consequently, during the stripping operation, it has been necessary to employ two operators, one at each end of the roll, to hold the ends of the shaft properly seated in the socket bearings. Moreover, as such socket bearings in the brackets necessarily open upwardly, it is necessary to give the roll a downward movement to position it on the brackets and an upward movement to remove it from the brackets which frequently results in the stripping roll being injured by accidentally striking one of the flats or other parts of the carding engine.

One of the objects of the present invention is to provide a novel and improved means for supporting the rolls of such devices which retains all of the advantages of the prior constructions, while doing away with the disadvantages.

With this object in view the features of the present invention comprise certain constructions, arrangements, and combinations of parts hereinafter described and claimed, the advantages of which will be obvious to those skilled in the art.

The several features of the present invention will be readily understood from the following description and accompanying drawings in which: Figure 1 is a side elevation of a portion of a carding engine and a card stripping device applied thereto embodying the several features of the present invention in their preferred form; Fig. 2 is a detail view in side elevation of a bracket and cooperating bearing block with these parts separated; Fig. 3 is a detail view in front elevation of a bearing block; Fig. 4 is a detail plan view of a bracket and bearing block in operative engagement; Fig. 5 is a plan view of a card stripping device and portions of the side frames of a carding engine.

The carding engine illustrated in part in the accompanying drawings comprises side frames 2, a card cylinder 4 mounted between the side frames the periphery of which is indicated by a dotted line in Fig. 1, and a card flat 6. In the illustrated embodiment of the present invention brackets 8 are adjustably secured to the outer sides of the side frames of the carding engine by means of bolts 10 which extend through elongated slots in the brackets and are screwed into the side frames. The forward ends of the brackets 8 are provided with vertically offset tongues 12 which are located substantially radial to the axis of the card cylinder. The upper side of each of the tongues 12 is provided with a flat portion 14 and the under side with a flat portion 15 parallel therewith and with an upwardly beveled portion 18.

The card stripping device illustrated in the drawings comprises the usual stripping roll 20 mounted in a casing 22 which is connected to a suitable vacuum apparatus through a flexible pipe 24. The stripping roll 20 is mounted on a shaft 26 which extends through and is journaled in the ends of the casing. On the left end of the shaft 26 is secured a pulley 28. In the illustrated embodiment of the present invention the ends of the shaft 26 extend through bearing blocks 30 which are located adjacent the ends of the casing. Each of the bearing blocks 30 is provided with a cylindrical portion 32 having a lining 35 in which the shaft is journaled. Each of the bearing blocks 30 is also provided with an upwardly offset portion 34. The offset portions 34 are each provided with a pair of rectangular lugs 36 which are spaced to form a rectangular channel or socket 38 corre-

sponding in cross-section to the tongues 12 of the brackets 8. The outer ends of the walls of the channels flare outwardly.

To bring the stripping device into operative position relatively to the card cylinder it is moved into position to cause the tongues 12 on the brackets 8 to engage between the lugs 34 on the bearing blocks. In order to firmly lock the stripping device in position and to determine the position to which it is proper to move the stripping device relatively to the card cylinder, the upper lugs 34 of the bearing blocks are provided with downwardly spring pressed locking pins or plungers 40, the heads of which when the device is moved into operative position snap into transverse grooves or sockets 42 in the upper sides of the tongues of the brackets 8. The heads of the plungers 40 are rounded to closely fit the sockets 42 and are mounted to slide in apertures 44 in the lugs 34. The plungers are pressed downwardly by means of springs 46 coiled about screws 48 secured to the heads of the plungers and interposed between the heads of the plungers and shoulders 50 in the recesses 44. The downward movement of the plungers are limited by the engagement of the heads of the screws 48 with the shoulders 50. The stripping device is held from longitudinal movement by the engagement of the inner walls of the channels 38 with the tongues 12.

It will be noted with this construction, that the stripping device is firmly held when in operative position, and that it may be moved readily into and out of operative position by movement radially to the axis of the card cylinder so that there is no danger of the stripping roll of the device being accidentally brought against the flats of the carding engine. The beveled surfaces 18 on the underside of the tongues 12 cooperate with the rear beveled end of the lower lugs of the bearing blocks 34 to relatively guide the bearing blocks and brackets into operative engagement.

The nature and scope of the present invention having been indicated and a device embodying the several features of the invention in their preferred form having been specifically described, what is claimed is:—

1. A portable device of the class described for operating upon a card of a carding engine having, in combination, a roll to act on the card, a casing in which the roll is mounted, bearings for the ends of the roll, brackets for attachment to the carding engine, and means cooperating with the bearings and brackets for locking the roll and casing in operative position when the device is applied to the carding engine, said means being capable of being released so as to permit the roll and casing to be removed as a unit from the carding engine.
2. A portable device of the class described

for operating upon a card cylinder of a carding engine having, in combination, a roll to act on the card, brackets for attachment to the carding engine, bearings for the ends of the roll adapted to be slid on the brackets in a direction to move the roll directly toward the axis of the card cylinder into operative position, and means cooperating with the bearings and brackets for locking the roll in operative position.

3. A device of the class described for operating upon a card of a carding engine having, in combination, a roll to operate on the card, bearings for the ends of the roll, brackets for attachment to the carding engine, and a spring pressed locking pin mounted in one of the bearings for engagement with one of the brackets to removably lock the roll from lateral displacement when the roll is moved into operative position.

4. A device of the class described for operating upon a card of a carding engine having, in combination, a roll to act on the card, bearings for the ends of the roll, brackets for attachment to the carding engine provided with sockets, and spring pressed locking pins mounted in the bearings to engage said sockets to lock the roll from lateral displacement when the roll is moved into operative position.

5. A device of the class described for operating upon a card of a carding engine having, in combination, a roll to act on the card, bearing blocks for the ends of the roll provided with transverse channels, brackets for attachment to the carding engine, members formed on the brackets to be received by said channels when the roll is moved into operative position, and interlocking members on the bearing blocks and said members of the brackets for locking the roll from lateral displacement when the roll is moved into operative position.

6. A device of the class described for operating upon a card of a carding engine having, in combination, a roll to act on the card, bearings for the ends of the roll, brackets for attachment to the carding engine, pairs of spaced lugs projecting from the bearings for the reception of the ends of the brackets between them, and cooperating interlocking members on the lugs and brackets for locking the lugs and brackets together and thereby lock the roll from lateral displacement when the roll is moved into operative position.

7. A device of the class described for operating upon a card of a carding engine having, in combination, a roll to act on the card, bearings for the ends of the roll, brackets for attachment to the carding engine having beveled ends, a pair of spaced rectangular lugs projecting from each of the bearings for the reception of the ends of the brackets between them, and spring pressed

locking pins mounted in one of the lugs of each pair to cooperate with members of the brackets to lock the roll from lateral displacement when the roll is in operative position.

8. A device of the class described for operating upon the card of a carding engine having, in combination, a roll to act on the card and capable of being moved into and out of operative position, and means acting automatically when the roll is moved into operative position for locking the roll from lateral displacement.

9. A device of the class described for operating upon the card of a carding engine having, in combination, a roll to act on the card, bearings for the ends of the roll, brackets for attachment to the carding engine, and cooperating interlocking members on the bearings and brackets constructed and arranged to engage when the roll is moved into operative position and to disengage when the roll is moved out of operative position.

JOSEPH J. SMITH.
